(57) **CLAIM**

The ornamental design for a foldable knife, substantially as shown and described.

DESCRIPTION

FIG. 1 is a perspective view of our new design showing it in an unfolded position.

FIG. 2 is a top view thereof.

FIG. 3 is a side view thereof.

FIG. 4 is a front view thereof.

FIG. 5 is a rear view thereof.

FIG. 6 is another side view thereof.

FIG. 7 is a bottom view thereof.

FIG. 8 is a side view thereof showing one end in a partially folded position.

FIG. 9 is a side view thereof showing one end in a folded position.

FIG. 10 is a side view showing the other end in a partially folded position.

FIG. 11 is a side view showing the other end in a folded position.

FIG. 12 is a perspective view thereof showing both ends in a folded position.

FIG. 13 is a top view thereof.

FIG. 14 is a side view thereof.

FIG. 15 is a bottom view thereof.

FIG. 16 is a front view thereof; and,

FIG. 17 is a rear view thereof.

The broken lines showing the utility blade is included for the purpose of illustrating environmental structure and forms no part of the claimed design.
